ANDREW E. GRISWOLD, OF SEATTLE, WASHINGTON

QUICK-MAKE-AND-BREAK SAFETY SWITCH

Application filed December 27, 1926. Serial No. 157,154.

This invention relates to improvements in electric switches, and more particularly to safety switches of the double break character used in circuits carrying heavy loads; the 5 principal object of the invention being to provide such switches with a quick "make" and quick "break" mechanism that is very positive in its action.

More specifically stated, the object of this 10 invention resides in the provision of a switch mechanism wherein springs under tension are used as a means for throwing the switch blade carriage from one position to another to bring the blades into and from the switch 15 jaws, and which act under the control of a hand lever to move the switch blades so as to make a very quick "break" or quick closing of the circuit.

Other objects of the invention reside in 20 the various details of construction and combination of parts of the switch mechanism, particularly in the blade carriage and travel bar construction.

In accomplishing these and other objects 25 of the invention, I have provided the improved details of construction the preferred forms of which are illustrated in the accompanying drawings, wherein—

Figure 1 is a side elevation of a switch 30 mechanism embodied by the present invention, a part of the switch housing being broken away for better illustration.

Figure 2 is a central, vertical section of the same.

Figure 3 is a front view of the switch mechanism, the front of the housing, and the control lever being removed for better illustration.

Figure 4 is a horizontal section taken on the 40 line 4—4 in Figure 3.

Figure 5 is a sectional detail showing the portion of the switch blades when in closed position and illustrating, in dotted lines, the movement of the actuating means permitted 45 by the lost motion connection between the switch carriage and travel bar.

Referring more in detail to the drawings—

In its preferred form of construction, the switch is contained within a sheet metal housing 50 designated at 1, having a door 2 closing

its upper front portion that is hingedly mounted, as at 3, so as to swing outwardly and downwardly to open position. The lower front portion of the housing is closed by a fixed panel 4 that is provided with a slot 5 through which is slidably extended a link 6 whereby connection is made between the switch mechanism within the housing and an actuating lever 7 that is pivotally mounted, as at 8, on a bracket 9 fixed to the outside 60 of the panel 4. The control lever 7, in this instance, extends downwardly from the pivot point and at its upper end is provided with an extension 10 adapted to engage with a lug 11 on the door 2, so as to prevent the door being 65 opened except at times when the lever is in the position it assumes when the switch is open.

Fixed to the back wall within the housing, 70 is an insulating panel 14 which may be of slate, ebony, or any other suitable material and, mounted on this, are paired, vertically aligned switch jaws 15—15', 16—16' and 17—17', as shown in Figure 3, each jaw being connected with a terminal 18 of a circuit. 75 Fixed in the panel midway of the upper and lower jaws of the switch and extending forwardly therefrom, in the same horizontal plane, are two parallel guide posts 19—19' on which the switch blade carriage is slidably mounted. This carriage comprises two bars of insulating material, designated at 20 and 20', between which three vertically disposed switch blades 21, 22 and 23 are rigidly clamped; the bars 20—20' being notched, as 80 shown at 24 in Figure 4, to receive the edges of the blades in such manner as to prevent their slipping from proper position. Extending through the bars 20—20' are tubular thimbles 25—25', which are clinched over 85 at their ends to draw the bars tightly against the blades and to hold all the parts rigidly and firmly together. Through these thimbles the posts 19—19' slidably extend and the carriage may be moved inwardly or outwardly 90 along these posts to bring the blades into or from the switch jaws.

Also, fixed in the bars 20—20', in parallel relation to the thimbles 25—25', are thimbles 26—26' within which bolts 27—27' are con- 100

tained. These bolts are slightly longer than the thimbles and at their outer ends are fixed by nuts 28—28' to a transverse travel bar 29', and at their inner ends are equipped with heads, or nuts, 30 which serve to limit the outward travel of the bolts in the thimbles. Coiled springs 31 are located within the thimbles about the bolts and these bear, at their inner ends, against the heads 30 and, 10 at their outer ends, against the plate 32 that overlies the outer ends of the thimbles and that yieldably urges the carriage toward the travel bar 29; the plate 32 being provided with apertures through which the bolts slidably extend.

15 The travel bar 29 has a plate 35 fixed to its outer face, centrally between the posts, and to this is operatively connected the inner end of the link 6 through which the carriage, by 20 movement of the control lever 7, is actuated inwardly or outwardly for the purpose of closing or opening the circuit.

25 Fixed within the housing 1, in parallel relation to the side walls and spaced therefrom, are plates 40 and 40' which have cut-out portions providing guide slots 41—41' through which the ends of the travel bar 29 extend and which permit movement of the bar toward or from the back of the housing. 30 Extending transversely between the plates, above and below the upper and lower rows of switch jaws as shown in Figures 2 and 3, are rods 42—42'. These are revolvably mounted and their ends extend slightly beyond the plates and have levers 43—43' fixed thereon.

35 The paired levers located at the same side of the housing are pivotally connected at their inner ends by means of short links 45 with the adjacent end of travel bar 29 and their outer ends are connected by a coiled spring 46 which is under considerable tension. When the switch is open the outer ends of the paired levers extend rearwardly at the 40 same angle with respect to the line of their pivot points and they terminate adjacent the rear wall of the housing, and the spring yieldably holds the switch in open position. When the switch is closed, the closing action 45 causes the outer ends of the levers to swing upwardly and when they pass over the dead center line of the pivot points, the spring then acts to throw the inner ends of the levers and the switch bar inwardly. The 50 levers on each cross rod are fixed rigidly thereto, so that all of the levers operate together to cross the dead center points at the same time.

55 With this construction, when it is desired 60 to move the switch from open position, as shown in Figures 1, 2 and 3, to closed position, as shown in Figure 5, the hand lever 7 is actuated inwardly, as to the dotted line position in Figure 2, and this, through the 65 connecting link 6, moves the travel bar 29

inwardly and, since the bar is seated against the switch blade carriage, the latter will be actuated inwardly along the guide posts. Inward movement of the travel bar 29 causes the levers 43—43' to swing forwardly and as their outer ends pass over the dead center line of the pivot points, the springs 46 cause the switch to be thrown quickly to snap the blades into the jaws.

70 When the switch is to be opened, the lever 7 is pulled outwardly. This causes the travel bar 29 also to be moved outwardly and the levers 43—43' to be swung rearwardly. During the initial outward movement of the travel bar there will be no movement of the switch carriage due to the fact that the grip of the jaws against the blades is made sufficient to overcome the pressure of the springs 31; however, when the heads 30 of the bolts 27—27' engage with the ends of the thimbles through which the bolts extend, the carriage 80 will be moved outwardly. Due to this lost motion connection, the outward movement of the carriage does not start until the levers 43—43' are about to pass over the dead center line of their mounting points, then as 85 they snap over, the switch is thrown open quickly. Without this lost motion connection, the switch blades would be unseated slowly from the jaws before the springs could 90 function to throw the switch and there would be an undesirable arcing due to this slow movement.

95 Having thus described my invention, what I claim as new therein and desire to secure by Letters-Patent, is:

100 1. A switch of the character described, comprising a mounting base, switch jaws on the base, guide posts fixed to the base, a carriage 105 slideable on the guide posts, blades mounted by the carriage and movable therewith into and from the jaws, a pivotally mounted control lever having a lost motion connection with the carriage and through which the carriage may be actuated toward or from the 110 jaws, and mechanism under spring tension for yieldably retaining the switch in "on" or "off" positions, and for throwing the carriage quickly between "on" and "off" positions after a predetermined movement by the control lever.

115 2. A switch of the character described, comprising a mounting base, switch jaws on the mounting base, guide posts fixed to the base, a carriage slideable on the posts, blades mounted by the carriage and movable therewith into and from the jaws, a travel bar having a lost motion connection with the carriage, a pivotally mounted control lever, a link connecting the lever with the travel bar, paired 120 levers pivotally mounted between their ends and having ends operatively connected with the travel bar, springs connecting the other ends of the paired levers and operable to yieldably retain the carriage at "on" or "off" 125 130

positions and to throw the carriage quickly from one position to the other incidental to a movement of the travel bar by the control lever that will carry the spring connected ends of said levers from one side to the other of the line of their mounting points.

3. A switch of the character described, comprising a mounting base, switch jaws on the base, guide posts fixed on the base, a carriage 10 slideable on the guide posts from and toward the jaws, switch blades mounted by the carriage and movable therewith into and from the jaws, a travel bar slideable on the posts, bolts fixed to the travel bar and extending 15 slidably through openings in the carriage and providing a lost motion connection between the carriage and bar, a pivotally mounted control lever, a link connecting the control lever with the travel bar, whereby it may be 20 actuated to move the carriage, paired levers pivotally mounted between their ends at opposite sides of the carriage, links connecting the inner ends of the levers with the ends of the travel bar, springs under tension connect- 25 ing the outer ends of the paired levers and operable to throw the levers to move the switch carriage quickly between "on" and "off" positions when the spring connected ends of said levers are moved by their con- 30 nection with the travel bar from one side to the other of the dead center line of the pivot points of the levers.

4. A switch of the character described, comprising a mounting base, switch jaws on the 35 base, guide posts fixed to the base, a carriage slideable on the posts, blades mounted by the carriage and movable therewith into and from the jaws, a travel bar adapted to engage with the carriage and to move it from "off" to "on" position, bolts fixed to the travel 40 bar and extending slidably through the carriage, nuts on the ends of the bolts whereby the carriage may be moved from "on" to "off" position, yieldable means for urging the carriage toward the travel bar, mechanism under 45 spring tension for throwing the travel bar quickly between "on" and "off" positions, a control lever and means connecting the control lever with the travel bar.

5. A switch of the character described comprising a housing, a mounting base within the housing, switch jaws on the base, guide posts fixed on the base, a carriage slideable on the posts toward and from the jaws, switch 55 blades mounted in the carriage and movable therewith into and from the jaws, a travel bar, bolts having ends fixed in the travel bar and with their other ends slidably mounted in the carriage and having nuts thereon for 60 limiting their travel, springs about the bolts and bearings against the nuts and carriage to urge the latter toward the travel bar, a pivotally mounted control lever, a link connected at one end with the travel bar and 65 connected at its other end by a pin and slot

connection with the lever, cross shafts ex- tended revolvably through the housing, levers fixed to the ends of said shafts, links connect- ing the inner ends of the levers with the ends of the travel bar, springs under tension connect- 70 ing the outer ends of the paired levers and operable to throw the levers to move the switch carriage quickly between "on" and "off" positions when the spring connected ends of said levers are moved by their con- 75 nection with the travel bar from one side to the other of the dead center line of the pivot points of the levers.

Signed at Seattle, Washington, this 26th day of November, 1926.

ANDREW E. GRISWOLD.
